Continuation of abandoned application Serial
No. 80,374, March 9, 1949, which is a division
of application Serial No. 731,126, February 26,
1947. This application March 10, 1952, Serial
No. 275,694

15 Claims. (Cl. 137—102)

1

Our invention relates to improvements in control valve mechanisms. Control valve mechanisms of the type to which our invention relates have particular utility in mine vehicles of the type known as "shuttle cars," but are not confined to such use.

"Shuttle cars" very commonly have provision for the supply of power to them including a reel on which a power cable is wound. Reel drive and control means must be provided so that the reels will wind up the cable when the cars are moving towards the point of connection of the cable to a source of power and such as to permit the drawing off of the cable when the cars are moving away from such point of connection, and also such that, when the cars move in courses or paths which involve a need for a shifting from a winding-in to a paying-out, or from a paying out to a winding-in, of the cable, this will be automatically accomplished. It is also important that when paying out ceases, conditions shall immediately be established in readiness for a winding-in operation, in order to prevent possibility of the cable's being run over, and to prevent an accumulation of slack which might interfere with the smooth winding of the cable. It is further, therefore, important to maintain some tension on the cable even during the time when it is being pulled off of the reel.

A very desirable apparatus for accomplishing the objectives mentioned is described and claimed in our application Serial No. 731,126, filed February 26, 1947, for Cable Reeling Mechanism, of which application this present application is a division. This apparatus, in its illustrative form there shown and described, includes a pump for supplying a hydraulic fluid, a motor-pump device to which the pump supplies fluid and which is operatively connected to the reel so that when such motor-pump device operates as a motor it drives the reel and so that it is driven by the reel when cable is unwound; together with means—the improved valve means of this present case, in the illustrative embodiment—controlled entirely by hydraulic pressures produced in the normal operations of the device for imposing on the motor-pump device a substantial pressure, say, for illustration but without limitation thereto, 300 p. s. i. when the reel is being driven in the winding-in direction; a pressure on the order, but without limitation thereto, of 100 p. s. i. during unwinding of the cable; and a pressure, again on the order, but without limitation thereto, of 300 p. s. i. when the reel is stationary, the latter pressure being automatically imposed upon the motor-pump device immediately after the reel comes to

2

rest after an unwinding operation. Such valve means also permits the free discharge, substantially without any back pressure, of the full volume of fluid displaced by the pump when the reel or drum is not being driven by the motor-pump device but is instead driving the latter as a pump and causing the fluid then pumped thereby to be discharged against a back pressure imposed upon the motor-pump device when cable is being drawn off the reel.

That apparatus includes an automatic valve mechanism which forms the subject matter of this divisional application. Such automatic valve mechanism includes, in a preferred embodiment, 15 valves operative respectively to determine the pressure imposed on the motor-pump device of such a system as is referred to when the cable is being wound in and to determine the back pressure imposed on the motor-pump device when the cable is being unwound, and an automatic shifter valve controlled at least in part by the pressure built up by the motor-pump device when the same is acting as a pump for shifting connections in such a manner that, whereas during winding in 20 of the cable the relief device having the higher setting is in control, the relief device having the lower setting shall become operative when cable is to be pulled off the reel, and the main pump discharge shall then be automatically relieved of substantially all back pressure. And in a preferred embodiment there also may be included in 25 the means for controlling the position of the shifter valve mentioned, arrangements operative to place in control of the pressure in the line between the pump and motor-pump device, the pressure relief valve with the higher setting, when the reel comes to a stop.

In more specific terms, the improved valve means may include, in a preferred embodiment thereof, a pair of pressure relief valves set at different pressures, a shifter valve, and a check valve, a supply passage, a vent passage, and a passage for connection to a device to be controlled by said valve means, the pressure relief valve having the higher setting having its supply side constantly in free communication with said supply passage and its discharge side constantly in free communication with said vent, said check valve also having its supply side constantly in free communication with said supply passage and having its discharge side constantly in free communication with said passage for connection to a device to be controlled, the pressure relief valve having the lower setting having its discharge side constantly in free communication with said vent,

and having its supply side connectible with said passage for connection to a device to be controlled under the control of said shifter valve, and said supply passage connectible with said vent under the control of said shifter valve, the latter, at its opposite ends subjected to the pressures in said supply passage and in said passage for connection to a device to be controlled.

When the pressure in the passage for connection to a device to be controlled by said valve means is less than the pressure in the supply passage, the shifter valve means is adapted to interrupt communication between the former passage and the supply side of the pressure relief valve having the lower setting and between the supply and vent passages, and upon a pressure in the passage for connection to a device to be controlled by said valve means higher than the pressure in the supply passage, said shifter valve means is adapted to connect the former passage to the supply side of the pressure relief valve having the lower setting, and to connect the supply passage to the vent passage.

An object of our invention is to provide an improved controlling valve mechanism. Another object of our invention is to provide an improved controlling valve mechanism including a plurality of selectively operative pressure relief valves and shifter valve means. A further object is to provide an improved control valve including a plurality of pressure relief valves and a shifter valve hydraulically controlled for the purpose of rendering one or the other of said relief devices effective to control the pressure in a line connectible to a device to be controlled by said valve means. Yet a further object of our invention is to provide an improved control valve mechanism including a plurality of differently set relief devices and a shifter valve constructed and arranged to render one or the other of said relief devices effective to control the pressures in a line to a device to be controlled by said valve means, and also to insure control by the relief device having the higher setting upon cessation of flow through the line connectible to a device to be controlled by said valve mechanism. Other objects and advantages of the invention will hereinafter more fully appear.

Referring to the drawings in which one illustrative embodiment which our invention may assume is shown:

Fig. 1 is a diagrammatic view illustrating a control system which we have chosen as a setting in which to illustrate our improved control valve mechanism.

Fig. 2 is an enlarged end view of the control valve mechanism, the view being taken from what might be called the top, if the parts shown in Fig. 2 be considered to have the same relationship in space as is indicated on the first figure of the drawings.

Fig. 3 is a view of the control valve mechanism of Fig. 2 viewed from the left hand side thereof with the mechanism in the position indicated in Fig. 1.

Fig. 4 is an enlarged view of the control valve mechanism, showing the same in the position indicated in Fig. 1.

Fig. 5 is an enlarged sectional view on the plane of the section line 5—5 of Fig. 4.

Fig. 6 is an enlarged sectional view on the plane of the line 6—6 of Fig. 3.

Fig. 7 is a sectional view on the same plane

and scale as Fig. 5, with parts shown in different relative positions.

Fig. 8 is a fragmentary section taken on the plane of the line 8—8 of Fig. 5.

Figs. 9 and 10 are views similar to Fig. 1, but showing the control valve mechanism in, as it were, developed or schematic views so that all the passages therethrough and elements thereof may be followed in their working operations.

Referring now to the drawings, and first to Figs. 1, 9 and 10, it will be observed, as a preliminary to the detailed description of the control valve mechanism which is the subject matter of this present application, that a source of hydraulic fluid is shown at 1, as, for example, a suitably disposed tank, receptacle or sump, to contain the necessary quantity of hydraulic fluid. The source 1 is connected by a suitable suction line 2 with a main pump 3, which is driven from any suitable source of power, not shown. The pump 3 delivers fluid under pressure to a line 4 which is connected with a valve mechanism 5, which is the particular subject matter of this application. The valve mechanism 5 has a connection 6, hereinafter sometimes referred to as a conduit and as a line, with a motor-pump device 7 operatively connected, as by a belt 8, with a cable reel 9 upon which a power supply cable 10 is wound. Let it here be noted again that while our invention is specifically described with reference to a control system for a cable reel carrying an electric cable for supplying current to electric motors, the same is not in any sense limited to such systems. The motor-pump device is connected with a conduit 11—a vent line—which leads back to the source 1, and a relief line 13 leads from the valve mechanism 5 to the line 11. The pump 3 is shown as of the intermeshing gear type, as is also the motor-pump device 7.

The valve mechanism 5 includes a supply chamber 16 to which hydraulic fluid is delivered by the conduit 4. From this chamber fluid may be delivered through a shifter valve chamber 17 back to the connection 13 leading to the source 1, or, as will shortly be described, to another chamber 18 which is connected with the conduit 6 leading to the device to be controlled, as illustrated to the motor-pump device 7, and the conduit 6 communicates also with the shifter valve chamber 17, as later described.

Desirably, the chambers 16 and 18 may be formed in line with each other, as shown in Figs. 5 and 7, and separated by a ported septum 20, which forms a valve seat 21, with which a check valve 22 is adapted to cooperate and against which said check valve is adapted normally to be maintained by a spring 23, which at one end rests against the check valve and at its other end rests upon a plug 24 with which the conduit 6 is threaded or otherwise suitably connected. The structure of this check valve 22 may be seen from Fig. 8; and it will be noted that this valve has a number of slots 25 in its periphery through which fluid may flow from the chamber 16 to the chamber 18 when the valve 22 is unseated. The supply or upstream side of the check valve communicates freely with the supply chamber 16 and its discharge or downstream side freely with the conduit 6.

The shifter valve receiving chamber 17 includes five annular chambers, each spaced from the next adjacent chamber by a ported partition. These annular chambers, starting from the top in Fig. 5, are numbered respectively 26, 27, 28, 29 and 30. A ported partition 31 separates the chambers 26

and 27. A ported partition 32 separates the chambers 27 and 28. Similarly, ported partitions 33 and 34 respectively separate the chambers 28 and 29 and the chambers 29 and 30. Each of the ported partitions has the port therethrough of the same size as each of the others, and these several ports are coaxially arranged so that their surrounding walls provide guidance for a spool-type or double headed shifter valve 36 comprising an upper hollow head 37 and a lower head 38, a connecting portion 39 of reduced cross section whose presence results in the provision between the adjacent surfaces of said heads of an annular fluid conducting groove or conduit 40, and a stop projection 41. The head 37, as indicated, has a recess 42 therein into which extends a spring 43 whose upper end in Fig. 5 contacts an abutment plug 44 suitably packed at 45 to prevent leakage. A passage 46 of relatively small diameter at its lower end 47 extends from the chamber 42 through the stop portion 41 of the valve 36. The stop portion of the valve is adapted to cooperate with a suitable abutment plug 48.

The annular chamber 26 communicates with the supply chamber 16 through a port or cored opening 50 (whether a bored port or a cored opening depending on whether the valve casing is machined from the solid or cast). Similarly, the annular space 27 communicates as at 51 with the chamber 16. The annular chamber 28 communicates through the conduit 13 with the conduit 11 leading to the source 1. The annular chamber 29 communicates through a port or opening 52 with a chamber 53 in a relief valve casing 54 shown in the drawings as a separate element from the main body of the valve mechanism as a whole, but obviously formable with it as a unit if desired. The annular space 30 communicates through an opening 55 with the chamber 18. The annular chamber 28 also communicates through a port opening 56 with a chamber 57 in another relief valve housing 58. The annular chamber 28 further communicates through an opening 59 with a chamber 60 in the relief valve casing 54. The annular chamber 26 communicates through an opening 61 with a chamber 62 in the relief valve housing 58. The chamber 53 is separated from the chamber 60 by a ported valve seat 64 with which a spring pressed relief valve 65 is adapted to cooperate. A spring 66 having a follower 67 adjustably loaded by an adjusting screw and nut mechanism 68 controls the compression of the spring 66, and thus determines the pressure at which the valve 65 will lift from the seat 64. The chamber 53 is at the upstream side of the valve 65, the chamber 60 at its downstream side. A valve seat 69 surrounding a port 70 extending between the chambers 57 and 62 is adapted to cooperate with a relief valve 71 pressed in a closing direction by a spring 72 which rests against a follower 73 whose position may be adjusted by suitable screw and nut mechanism 74. The chamber 62 is at the upstream side of valve 71, the chamber 57 at its downstream side. It will be noted that when the valve 36 is in top position, it does not prevent communication between the chamber 16 and the port 70. The normal compression of the spring 72 will be much higher than the normal compression of the spring 66 when they are controlling valves having equal areas subjected to pressures tending to unseat such valves. For example, it may require a liquid pressure of 300 p. s. i. in chamber 62 to unseat valve 71 while, for example, a pressure of 100 p. s. i. in chamber 53 will suffice to unseat valve 65.

The pump 3 may be considered, for the purpose of describing the mode of operation of the embodiment of our invention which has been explained above, to be driven continuously while the vehicle is in use. Accordingly, it is taking in liquid from the source 1 through the conduit 2 and discharging it through the conduit 4 into the chamber 16, and the fluid so delivered to the chamber 16 must go somewhere. Obviously, from what has been said, the fluid when conditions are such that the cable can be wound in, may at least in part go past the check valve 22 and through the conduit 6 and into the motor-pump device 7 and drive the latter in a direction to effect winding-in of the cable 10, and then pass back to the source 1 through the conduit 11. Because the rate of winding-in of the cable will be controlled by the rate at which the vehicle moves in the direction in which the cable extends, it will be evident that all of the liquid pumped by the pump 3 cannot pass through the motor-pump device 7, under ordinary circumstances, at least, and accordingly provision is made for the return of the excess liquid discharged by the pump 3 to the line 11 through the connection 13. As considerable power must be exerted by the motor-pump device 7 to effect winding-in of the cable at the desired maximum rate, the excess fluid must not be allowed to pass through the connection 13 so readily that the necessary pressure will not be maintained in the supply connection 6 to the motor-pump device 7. Accordingly, as above indicated, the compression of the spring 72 which controls the relief valve 71 will be made sufficient to compel the desired pressure to be maintained in the chamber 16 and in the conduit 6. For example, a pressure of 300 p. s. i. may be maintained in the fluid supply connections to the motor-pump device 7 by the appropriate setting of the spring 72. It will be noted that from the chamber 16 the port 50 opens into the annular chamber 26 and that the shifter valve 36 can never shut off communication through the chamber 26 between the port 50 and the opening 61, and accordingly that whenever the pressure in the port 70 is high enough to unseat the relief valve 71 fluid may pass into the chamber 57 and through the port 56, and, referring to Figs. 6 and 7, through the chamber 28 to the conduit 13 and so back to the source 1 by way of the conduit 11. In Figs. 9 and 10, because of the desirability of avoiding overlapping ports, the connection of the conduit 13 with the chamber 28 is shown as made via a portion of the conduit 56 instead of opening into the chamber 28 separately from the port 56 and at right angles to the communication of that port with the chamber 28. Fig. 10, subject to the understanding just expressed, may be considered to show the normal position of the parts during the operation of the motor-pump device 7 in a direction to effect winding-in of the cable 10; in other words, the mode of operation which occurs when the vehicle is moving in a direction to shorten the free length of the cable. It will be observed that the shifter valve 36 occupies at this time the position shown in Figs. 5, 6 and 10, being so held by reason of the fact that the hydraulic pressure on its lower end is less than the hydraulic pressure on its upper end by the amount occasioned by the presence of the spring 23 and that, moreover, the spring 43 operates to hold the shifter valve 36 in the position mentioned.

Let it now be supposed that the vehicle is brought to a stop. This will mean that the motor-pump device 7 will no longer drive the reel to

wind in the cable, but nothing will occur in the controlling apparatus which will result in a movement of this shifter valve 36 to reduce the pressure imposed on the motor-pump device 7, and so the cable tension will be maintained undiminished when the vehicle is at a standstill.

Suppose now that the vehicle is caused to move in a direction which will necessitate the unwinding of the cable from the reel in order for such motion to take place. The motor-pump device 7 will then be driven in the opposite direction, and initially against the full pressure maintained by the setting of the relief valve device 71. However, the instant that the motor-pump device commences to draw fluid from the source 1 through the conduit 11 and to discharge into the conduit 6, the valve 22 will seat, and the only passage for flow of the fluid which can be established will be one opened by upward movement of the shifter valve 36 to the position shown in Figs. 7 and 9; and, because the pressure which will be built up momentarily may be in excess of the pressure imposed by the pump 3, which cannot exceed 300 p. s. i., or whatever other selected pressure may be fixed by the relief valve mechanism 71, the valve 36 will move upward to the position mentioned. When this occurs the fluid pumped by the main pump 3 will pass from the chamber 16 through the port 51 into the chamber 27, through the groove between the heads of the shifter valve into the chamber 28, and freely through the conduits 13 and 11 back to the source. Note that the back pressure on the main pump 3 has been completely removed except for such pressure as friction of the liquid in the passages may involve. Upward movement of the shifter valve 36 will also open a passage from the chamber 39 to the chamber 29, and, when the valve 65 is unseated, through the chamber 60 and port 59 to the chamber 28 and through the latter and by way of the conduits 13 and 11 back to the source. The valve 65 is unseated at a much lower pressure, as above indicated, than the valve 71, say, at a pressure of 100 p. s. i. in the chamber 53, and accordingly the tension on the cable 10 will be substantially reduced and the reel may be turned backwards, driving the motor-pump device 7 as a pump, with a much lower pressure in the line 6 than during the operation of the motor-pump device as a motor.

Now let it be assumed that the vehicle stops. The motor-pump device no longer acts as a pump and no longer delivers fluid through the conduit 6. The passage 46, 47 permits equalization of pressures at the opposite ends of the shifter valve 36 practically immediately, and the spring 43 forces the shifter valve back to the position shown in Figs. 5, 6 and 10. This interrupts communication between the passages 52 and 55 and between the chamber 16 and the conduit 13. Accordingly the pressure of the fluid in the line 6 and chamber 16 will build up to the value at which the relief valve 71 will be unseated. Therefore it will be evident that when the vehicle comes to a stop conditions will automatically result which will cause the motor-pump 7 to be subjected to the higher pressure necessary for most efficient winding in operations when the vehicle commences to move in the direction where winding-in of the cable is needed. Indeed the cable tension will be immediately increased.

From the foregoing description, it will be evident that we have provided an improved automatic control valve mechanism in which a shifter valve, automatically controlled, places differently

set relief valves in control of the critical pressure in accordance with different operations of the apparatus controlled and is adapted automatically to provide a free discharge for the normal operating fluid when it is not being used for motor actuation, thereby reducing power and avoiding excessive heating.

More specifically, the improved valve means will be noted to include a pair of pressure relief valves set at different pressures, a shifter valve, and a check valve, a supply passage, a vent passage, and a passage for connection to a device to be controlled by the valve means, the pressure relief valve with the higher setting, and the check valve each having its supply side constantly in free communication with the supply passage, the two pressure relief valves each having their discharge sides in free communication with said vent, the pressure relief valve with the lower setting having its supply side connectible with the passage for connection to a device to be controlled and the supply chamber connectible to the vent, both under the control of the shifter valve, and the shifter valve having opposed areas subjected to supply chamber pressure and to the pressure in the passage for connection to a device to be controlled, whereby when the pressure in said latter passage is less than the pressure in the supply passage the shifter valve will interrupt communication between the latter and the vent and between the supply side of the relief valve having the lower setting and the passage connectible to a device to be controlled, and when the pressure in the latter passage exceeds supply chamber pressure, the shifter valve means connects such passage to the supply side of the relief valve having the lower setting and the supply chamber to the vent. In certain of the claims the passage for connection to a device to be controlled by the valve mechanism, which passage is connected by the conduit 6 to the motor-pump device 7, is referred to, i. e., is defined, for brevity, as a work passage.

This application is a continuation of our co-pending application Ser. No. 80,374, filed March 9, 1949, now abandoned, which in turn is a division of our co-pending application Ser. No. 731,126, filed February 26, 1947.

While there is in this application specifically described one form which the invention may assume in practice, it will be understood that this form of the same is shown for purposes of illustration and that the invention may be modified and embodied in various other forms without departing from its spirit or the scope of the appended claims.

We claim:

1. In combination, in a valve mechanism, a casing providing chambers having in them respectively a shifter valve, two relief valves, and a check valve, an external inlet connection having communication with one end of said shifter valve containing chamber and also with said chamber at a point between the ends of the latter and also with said check valve and with one of said relief valves, an external vent connection communicating with the chambers containing each of said relief valves and with said shifter valve chamber at a different point between the ends of the latter, a connection between the other relief valve and said shifter valve chamber at still a different point therein, and a third external connection communicating with the other end of said shifter valve chamber and with said check valve chamber.

2. In combination, in a valve mechanism, a casing providing chambers having in them respectively a shifter valve, two relief valves having different settings, and a check valve, an external inlet connection having communication with one end of said shifter valve containing chamber and also with said chamber at a point between the ends of the latter and also with said check valve and with one of said relief valves, an external vent connection communicating with the chambers containing each of said relief valves and with said shifter valve chamber at a second and different point between the ends of the latter, a connection between the other relief valve and said shifter valve chamber at a third point between the ends of the latter, and a third external connection communicating with the other end of said shifter valve chamber and with said check valve chamber, said third point being nearer said other end of said shifter valve chamber than said second point is.

3. In combination, in a valve mechanism, casing means providing chambers including a shifter valve chamber and two relief valve chambers, a supply chamber, and a check valve chamber, a shifter valve in said shifter valve chamber, relief valves, having different loadings, in said relief valve chambers, a check valve in said check valve chamber, means placing said supply chamber in communication with a connection at the exterior of said casing means, means establishing communication between said check valve chamber and a connection at the exterior of said casing means, means establishing communication between an intermediate point in said shifter valve chamber and a connection at the exterior of said casing means, means establishing communication between said supply chamber and one end of said shifter valve chamber, means establishing communication between said check valve chamber and the other end of said shifter valve chamber, means establishing communication between each of said relief valve chambers and the exterior of said casing means, means establishing communication between said supply chamber and the seat end of one of said relief valve chambers, means for establishing communication between the supply chamber and the seat end of said check valve chamber, means establishing communication between said shifter valve chamber and the seat end of the other of said relief valve chambers, and means establishing another communication between said supply chamber and said shifter valve chamber.

4. In combination, in a valve mechanism, casing means providing chambers including a shifter valve chamber and two relief valve chambers, a supply chamber, and in alignment with said supply chamber, a check valve chamber, a shifter valve in said shifter valve chamber, relief valves, having different loadings, in said relief valve chambers, a check valve in said check valve chamber, means placing said supply chamber in communication with a connection at the exterior of said casing means, means establishing communication between said check valve chamber and a connection at the exterior of said casing means, means establishing communication between an intermediate point in said shifter valve chamber and a connection at the exterior of said casing means, means establishing communication between said supply chamber and one end of said shifter valve chamber, means establishing communication between said check valve chamber and the other end of said shifter valve chamber.

5. In combination, in a valve mechanism, a supply chamber, means establishing communication between each of said relief valve chambers and the exterior of said casing means, means establishing communication between said supply chamber and the seat end of one of said relief valve chambers, means for establishing communication between the supply chamber and the seat end of said check valve chamber, means establishing communication between said shifter valve chamber and the seat end of the other of said relief valve chambers, and means establishing another communication between said supply chamber and said shifter valve chamber.

10 15 20 25 30 35 40 45 50 55 60 65 70 75

5. In combination, in a valve mechanism, casing means providing chambers including a shifter valve chamber and two relief valve chambers, a supply chamber, and a check valve chamber, a shifter valve in said shifter valve chamber, relief valves, having different loadings, in said relief valve chambers, a check valve in said check valve chamber, means placing said supply chamber in communication with a connection at the exterior of said casing means, means establishing communication between said check valve chamber and a connection at the exterior of said casing means, means establishing communication between an intermediate point in said shifter valve chamber and a connection at the exterior of said casing means, means establishing communication between said supply chamber and one end of said shifter valve chamber, means establishing communication between said check valve chamber and the other end of said shifter valve chamber, means establishing communication between each of said relief valve chambers and the exterior of said casing means, means establishing communication between said supply chamber and the seat end of one of said relief valve chambers, means for establishing communication between the supply chamber and the seat end of said check valve chamber, means establishing communication between said shifter valve chamber and the seat end of the other of said relief valve chambers, means establishing another communication between said supply chamber and said shifter valve chamber, and means for biasing said shifter valve towards one end of its chamber.

6. In combination, in a valve mechanism, casing means providing chambers including a shifter valve chamber and two relief valve chambers, a supply chamber, and a check valve chamber, a shifter valve in said shifter valve chamber, relief valves, having different loadings, in said relief valve chambers, a check valve in said check valve chamber, means placing said supply chamber in communication with a connection at the exterior of said casing means, means establishing communication between said check valve chamber and a connection at the exterior of said casing means, means establishing communication between an intermediate point in said shifter valve chamber and a connection at the exterior of said casing means, means establishing communication between said supply chamber and one end of said shifter valve chamber, means establishing communication between said check valve chamber and the other end of said shifter valve chamber, means establishing communication between each of said relief valve chambers and the exterior of said casing means, means establishing communication between said supply chamber and the seat end of one of said relief valve chambers, means for establishing communication between the supply chamber and the seat end of said check valve chamber, means establishing communication between said shifter valve chamber and the seat end of the other of said relief valve chambers, means establishing another communication between said supply chamber and said shifter valve chamber, and means for biasing said shifter valve towards one end of its chamber.

pair of pressure relief valves set at different pressures, a shifter valve, and a check valve, a supply passage, a vent passage, and a work passage for connection to a device to be controlled, means for continuously connecting the supply side of the pressure relief valve having the higher setting in free communication with the supply passage and the discharge side of the pressure relief valve having the higher setting continuously in free communication with the vent passage, means for connecting the supply side of said check valve continuously in free communication with the supply passage and for continuously connecting the discharge side of said check valve in free communication with the work passage, means for continuously connecting the discharge side of the pressure relief valve having the lower setting in free communication with said vent passage, means controlled by said shifter valve for connecting the supply side of said pressure relief valve having the lower setting with the work passage, means controlled by said shifter valve for connecting said supply passage with said vent passage, and means for subjecting the opposite ends of said shifter valve respectively to the pressure in the supply passage and to the pressure in the work passage.

11. In combination, in a valve mechanism, a pair of pressure relief valves set at different pressures, a shifter valve, and a check valve, a supply passage, a vent passage, and a work passage for connection to a device to be controlled, means for connecting the supply sides of the pressure relief valve with a higher setting and the check valve constantly in free communication with the supply passage, means for connecting the discharge sides of the two pressure relief valves constantly in free communication with the vent passage, passage means for connecting the supply side of the pressure relief valve with the lower setting with the work passage and for connecting the supply passage to the vent passage, both under the control of the shifter valve, said shifter valve having opposed areas facing longitudinally thereof, and means for subjecting one of said areas to the supply passage pressure and the other to the pressure in the work passage, whereby, when the pressure in said latter passage is less than the pressure in the supply passage the shifter valve will be moved in one direction, and when the pressure in the work passage exceeds supply passage pressure the shifter valve will be moved in the opposite direction, said shifter valve controlled passage means so arranged that in the first mentioned position of the shifter valve such valve will interrupt communication between the supply passage and the vent passage and between the supply side of the relief valve having the lower setting and the work passage, and in the second position of the shifter valve the latter will connect the work passage to the supply side of the relief valve having a lower setting and connect the supply passage to the vent passage.

12. In combination, in a valve mechanism, a pair of pressure relief valves, a shifter valve, and a check valve a supply passage, a vent passage, and a work passage for connection to a device to be controlled, means for continuously connecting the supply side of one of said pressure relief valves in free communication with the supply passage and the discharge side of said same pressure relief valve continuously in free communication with the vent passage, means for connecting the supply side of said check valve continuously in free communication with the supply passage and

continuously connecting the discharge side of said check valve in free communication with the work passage, means for continuously connecting the discharge side of the other pressure relief valve in free communication with the vent passage, means controlled by the shifter valve for connecting the supply side of said last mentioned pressure relief valve with the work passage, means controlled by the shifter valve for connecting the supply passage with the vent passage, and means for subjecting the opposite ends of the shifter valve respectively to the pressure in the supply passage and to the pressure in the work passage.

13. In combination, in a valve mechanism, a pair of pressure relief valves set at different pressures, a shifter valve, and a check valve, a supply passage, a vent passage, and a work passage for connection to a device to be controlled, means for continuously connecting the supply side of one of said pressure relief valves in free communication with the supply passage and the discharge side of said same pressure relief valve continuously in free communication with the vent passage, means for connecting the supply side of said check valve continuously in free communication with the supply passage and continuously connecting the discharge side of said check valve in free communication with the work passage, means for continuously connecting the discharge side of the other pressure relief valve in free communication with the vent passage, means controlled by the shifter valve for connecting the supply side of said last mentioned pressure relief valve with the work passage, means controlled by the shifter valve for connecting the supply passage with the vent passage, means for subjecting the opposite ends of the shifter valve respectively to the pressure in the supply passage and to the pressure in the work passage, and means for providing a restricted communication between the opposite ends of said shifter valve.

14. In combination, in a valve mechanism, a casing providing a chamber having in it a fluid thrown shifter valve, said casing having associated with it a first and a second relief valve and a check valve each having an upstream and a downstream side, a fluid inlet having connections with the upstream side of said check valve and of said first relief valve, a connection with said shifter valve chamber controllable by said shifter valve and a connection for transmitting fluid for throwing said shifter valve in one direction, an external vent connection for said shifter valve chamber connectible by said shifter valve with the first mentioned connection with said shifter valve chamber, connections for conducting to vent fluid from the downstream sides of both of said relief valves, a connection between the upstream side of said second relief valve and said shifter valve chamber at a point alternatively covered and uncovered by said shifter valve, and an external connection communicating with the downstream side of said check valve chamber and having a connection for transmitting fluid for throwing said shifter valve oppositely to said first direction.

15. In combination, in a valve mechanism, a casing providing a shifter valve chamber containing a shifter valve, and having associated with it two relief valves and a check valve each having an upstream and a downstream side, a fluid supply connection communicating with the upstream side of said check valve and of one of said relief valves and further communicating with said shifter valve chamber both at one

15

end of the latter and at a point spaced from such end but between the two ends of said shifter valve chamber, a vent connection communicating with said shifter valve chamber at a point between the ends of the latter different from the first mentioned point, connections between the downstream sides of each of said relief valves and the exterior of said casing, a connection between the upstream side of the other relief valve and said shifter valve chamber at a point in the latter between its ends and different from each of said other two points, and a work connection communicating with the other end of

10

16

said shifter valve chamber and with the downstream side of said check valve.
